UNITED STATES PATENT OFFICE.

JOHN J. HENNESSEY, OF MILWAUKEE, WISCONSIN.

FRICITION DRAFT-RIGGING FOR RAILWAY-CARS.

SPECIFICATION forming part of Letters Patent No. 716,416, dated December 23, 1902.

Application filed October 27, 1902. Serial No. 128,848. (No model.)

To all whom it may concern:

Be it known that I, JOHN J. HENNESSEY, a citizen of the United States, residing at Milwaukee, in the county of Milwaukee and State 5 of Wisconsin, have invented a new and useful Improvement in Friction Draft-Rigging for Railway-Cars, of which the following is a specification.

My invention relates to friction draft-rigging for railway-cars.

The object of my invention is to provide a friction draft-rigging of a simple, strong, efficient, and durable construction, in which the transversely-acting spring and double-incline 15 friction-block may be located beneath the draft-iron and act against its lower side and which may be cheaply manufactured and readily applied to or removed from the car and which will operate to properly and effi- 20 ciently cushion both light and heavy strains or blows.

My invention consists in the means herein shown and described by which I accomplish this result—that is to say, it consists, in connection with a draw-bar and draft-iron or extension in line therewith and having double-incline friction-faces on its lower side, a stationary friction-plate in sliding engagement with the upper horizontal face of the draft- 25 iron, and a transversely-movable friction-block below the draft-iron acted upon by a transversely-arranged spring and having double-incline friction-faces, of a pair of side plates or stop-castings secured to the draft-timbers or center sills of the car and provided 30 each with a recess or socket in its central upper portion to receive, hold, and anchor in position one end or edge of the stationary friction-plate and with a pair of guides for 35 the transversely-movable friction-block to reciprocate vertically in while being held from longitudinal movement and also with a pair of downwardly-projecting lugs to receive the removable spring-seat against which the lower 40 end of the spring bears. The side plates or stop-castings are also provided with horizontally-extending wings which abut against and interlock and engage each other and serve to secure the two side plates or stop- 45 castings together at their upper portions or above the draft-iron. My invention also consists in the novel construction of parts and

devices and in the novel combinations of parts and devices herein shown or described.

In the accompanying drawings, forming a 55 part of this specification, Figure 1 is a central vertical longitudinal section, on line 1 1 of Fig. 2, of a friction draft-rigging embodying my invention. Fig. 2 is a plan view. Fig. 3 is a cross-section on line 3 3 of Fig. 4. Fig. 60 4 is a detail perspective view of the removable spring-seat. Fig. 5 is a detail perspective view of one of the side plates or stop-castings. Fig. 6 is a perspective view of the stationary friction-plate, and Fig. 7 is a per- 65 spective view of the draft-iron.

In the drawings like letters of reference indicate like parts in all the figures.

In said drawings, A represents the draft-timbers; A', the center sills; A², the cross-sill; 70 A³, the buffer-block; A⁴, the buffer-plate, and A⁵ the carry-iron. B is the draw-bar of the coupler B', these parts being of any suitable construction.

D is the sliding friction draw-bar extension 75 or draft-iron, the same being directly in line with the draw-bar and connected thereto by a clip or yoke b, passing through an eye d in the draw-bar extension or draft-iron.

F F are a pair of side plates or stop-castings fitting between the draft-timbers and securely attached thereto by bolts f. Each of the stop-castings F is provided at its central upper portion with a recess or socket f' to receive the end g of the stationary friction- 80 plate G, so as to securely hold and anchor the same in position above the longitudinally-movable draft-iron D, and in sliding frictional engagement with the straight friction upper face d² of the draft-iron and in the central line of draft. Each of the stop-castings F is also furnished with transverse or 85 upright guides or flanges f² to guide and hold longitudinally in position the transversely-movable friction-block H. The guides or flanges f² are extended at their lower ends to form downwardly-projecting lugs f³ to receive, support, and anchor in position the removable spring-seat or barrel K, against which the lower end of the transversely-acting 90 spring K' bears. Both of the stop-castings F are also provided or preferably provided on their inner faces with horizontal strengthening ribs or flanges f⁴ and vertical ribs or 95

- flanges f^5 , the latter forming guide-faces for the transversely-movable friction-block H. Each of the side plates or stop-castings F is also provided with a horizontally-projecting 5 wing f^6 , having interlocking or interengaging notches or tongues f^7 and f^8 , and which abutting or interlocking wings are secured together by bolts f^9 , so as to give additional strength to the structure as a whole.
- 10 The draft-iron D has on its lower side double-incline friction-faces d^3 d^4 , and the transversely-movable friction-block H has corresponding double-incline friction-faces h^3 h^4 , which bear against the double-incline friction-faces on the draft-iron when the draft-iron moves longitudinally under either pulling or buffing strains. Bridging the double-incline friction-faces d^3 d^4 on the draft-iron there is an integral central longitudinal web 15 d^5 to strengthen the draft-iron and which fits in a corresponding longitudinal groove or slot h^3 in the transversely-movable friction-block. The friction-block H is also provided with an integral downwardly-projecting 20 flange or cup h^3 to receive and guide the spring K'. To prevent any tendency of the draft-iron to tilt up or down on the double-incline friction-block H as a pivot, projecting guides or flanges K^4 for supporting or 25 guiding the draft-iron may be provided on the removable spring seat or barrel K, especially in cases where, as illustrated in the drawings, the draft-iron is provided with only a single pair of incline friction-faces and with 30 a single transversely-movable friction block and spring.

To remove the draft-iron and transversely-movable friction block and spring, all that is required is to take out the cotter-bolts K^2 , 40 when the removable spring-seat K will drop down, and thus permit the withdrawal of the spring, friction-block, and draft-iron. My improved friction draft-rigging may be thus very quickly and conveniently removed from 45 the car and replaced.

The draft-iron D has stop-shoulders d^6 d^7 , which engage corresponding shoulders f^{10} f^{11} on the side plates or stop-castings to limit the longitudinal movement of the draft-iron and 50 draw-bar.

I claim—

1. In a friction draft-rigging for railway-cars, the combination with a draw-bar, of a draft-iron in line therewith and having double-incline friction-faces on its lower side, a stationary friction-plate above and in line with the draw-bar and in sliding frictional engagement with the upper side of the draft-iron, a transversely-movable friction-block 55 below the draft-iron and having double-incline friction-faces engaging the incline friction-faces on the draft-iron, a transversely-arranged spring acting against said friction-block, and a pair of side plates or stop-castings having each a recess or socket at its upper portion to receive and anchor one end or

edge of said stationary friction-plate, and provided with upright guides or flanges to guide and hold in longitudinal position the transversely-movable friction-block, substantially as specified. 70

2. In a friction draft-rigging for railway-cars, the combination with a draw-bar, of a draft-iron in line therewith and having double-incline friction-faces on its lower side, a 75 stationary friction-plate above and in line with the draw-bar and in sliding frictional engagement with the upper side of the draft-iron, a transversely-movable friction-block below the draft-iron and having double-incline friction-faces engaging the incline friction-faces on the draft-iron, a transversely-arranged spring acting against said friction-block, and a pair of side plates or stop-castings having each a recess or socket in its upper portion to receive and anchor one end or edge of said stationary friction-plate, and provided with upright guides or flanges to guide and hold in longitudinal position the transversely-movable friction-block, and a 80 removable spring seat or barrel secured to said stop-castings for the lower end of the spring to bear against, substantially as specified. 85

3. In a friction draft-rigging for railway-cars, the combination with the draw-bar, of a draft-iron in line therewith and having double-incline friction-faces on its lower side, a stationary friction-plate above and in line with the draw-bar and in sliding frictional 90 engagement with the upper side of the draft-iron, a transversely-movable friction-block below the draft-iron and having double-incline friction-faces engaging the incline friction-faces on the draft-iron, a transversely-arranged spring acting against said friction-block, and a pair of side plates or stop-castings having each a recess or socket at its upper portion to receive and anchor one end or edge of said stationary friction-plate, and provided with upright guides or flanges to 95 guide and hold in longitudinal position the transversely-movable friction-block, and a removable spring seat or barrel secured to said stop-castings for the lower end of the spring to bear against, substantially as specified. 100

4. In a friction draft-rigging for railway-cars, the combination with a draw-bar, of a draft-iron in line therewith and having double-incline friction-faces on its lower side, a stationary friction-plate above and in line with the draw-bar and in sliding frictional 105 engagement with the upper side of the draft-iron, a transversely-movable friction-block below the draft-iron and having double-incline friction-faces engaging the incline friction-faces on the draft-iron, a transversely-arranged spring acting against said friction-block, and a pair of side plates or stop-castings having each a pair of downwardly-projecting lugs 110 to receive said removable spring seat or barrel, substantially as specified. 115

- having each a recess or socket at its upper portion to receive and anchor one end or edge of said stationary friction-plate and provided with upright guides or flanges to guide and hold in longitudinal position the transversely-movable block, said stop-castings having at their upper portions horizontally-projecting and interengaging wings to secure the stop-castings together, substantially as specified.
- 10 5. In a friction draft-rigging for railway-cars, the combination with a draw-bar, of a draft-iron in line therewith and having double-incline friction-faces on its lower side, a stationary friction-plate above and in line with the draw-bar and in sliding frictional engagement with the upper side of the draft-iron, a transversely-movable friction-block below the draft-iron and having double-incline friction-faces engaging the incline friction-faces on the draft-iron, a transversely-arranged spring acting against said friction-block, and a pair of side plates or stop-castings having each a recess or socket at its upper portion to receive and anchor one end or edge of said stationary friction-plate and provided with upright guides or flanges to guide and hold in longitudinal position the transversely-movable friction-block, and a removable spring seat or barrel secured to said stop-castings for the lower end of the spring to bear against said stop-castings having at their upper portions horizontally-projecting and interengaging wings to secure the stop-castings together, substantially as specified.
- 15 20 25 30 35 40 45 50 55
6. In a friction draft-rigging for railway-cars, the combination with a draw-bar, of a draft-iron in line therewith and having double-incline friction-faces on its lower side, a stationary friction-plate above and in line with the draw-bar and in sliding frictional engagement with the upper side of the draft-iron, a transversely-movable friction-block below the draft-iron and having double-incline friction-faces engaging the incline friction-faces on the draft-iron, a transversely-arranged spring acting against said friction-block, and a pair of side plates or stop-castings having each a recess or socket at its upper portion to receive and anchor one end or edge of said stationary friction-plate and provided with upright guides or flanges to guide and hold in longitudinal position the transversely-movable friction-block, and a removable spring seat or barrel secured to said stop-castings for the lower end of the spring to bear against said stop-castings having at their upper portions horizontally-projecting and interengaging wings to secure the stop-castings together, substantially as specified.
